UNITED STATES PATENT OFFICE.

HARRY B. COX, OF CINCINNATI, OHIO.

ELECTRIC BELL CORD.

SPECIFICATION forming part of Letters Patent No. 340,425, dated April 20, 1886.

Application filed January 23, 1886. Serial No. 189,487. (No model.)

To all whom it may concern:

Be it known that I, HARRY B. COX, of Cincinnati, in the county of Hamilton and State of Ohio, have invented certain new and useful Improvements in Electric Bell Cords; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to bell-cords for railway-trains; and it consists in the improved construction of electric bell-cords hereinafter fully described, and specifically pointed out in the claims.

In the accompanying drawings, Figure 1 represents an interior view of a portion of a railway-car, showing the manner in which my invention is applied for use. Fig. 2 is a perspective view of my improved bell-cord, the rubber or other flexible outer tube being removed. Fig. 3 is a perspective view, a portion of said outer tube being broken away; and Fig. 4 is a longitudinal central section through the device complete.

Like letters of reference mark the same parts wherever they occur in the several figures.

Referring to the drawings by letters of reference, A is the roof of an ordinary passenger-car, from which usually depend brackets or hangers B, for receiving and suspending the bell-cord, which passes through openings in the ends of the cars and reaches from the engine to the rear of the train. These parts are of ordinary construction, and are merely shown for the purpose of illustrating the manner (well known) of suspending any bell-cord. Of course any other suitable means might be used for this purpose, my invention relating to the construction of a bell-cord, and not to the manner of suspending it.

My bell-cord C is constructed as follows: D marks a rubber or other flexible tubing, com-

posed of insulating material. E E' are two wires contained within the said tubing and held apart at intervals by means of blocks F F', of insulating material, which are disk-shaped and of a size sufficient to fill the outer tube when placed therein. On opposite sides these insulating disks are provided with notches to receive the wires E E', said notches being marked f f'. The wires E E', separated by the insulators and resting in the notches therein, are placed within the rubber tubing, being normally kept apart therein. On the engine is placed an electric bell and a suitable battery, to the poles of which the wires E E' are attached. There being no contact between these wires normally the circuit is normally incomplete and must be completed in order to ring the bell. This can be done at any point in the length of the bell-cord between the insulators by simply squeezing the outer tubing until the wires touch each other. This completes the circuit and rings the bell.

Having thus fully described my invention, what I claim as new, and desire to secure by Letters Patent of the United States, is—

1. An electric bell cord consisting of a rubber tube, a series of insulating-disks of a diameter equal to the interior diameter of said tube, located therein at intervals, and two wires held apart and against the interior of the tube by said insulators, as set forth.

2. The combination, with the continuous rubber tube D, of the insulating disks F, of a diameter to fit said tube, provided with notches in their peripheries, and the two wires E E', passing through said notches and held apart by means of said insulators, as set forth.

In testimony that I claim the foregoing as my own I hereunto affix my signature in presence of two witnesses.

HARRY B. COX.
